UNITED STATES PATENT OFFICE.

HENRY A. WISE WOOD, OF NEW YORK, N. Y., ASSIGNOR, BY MESNE ASSIGNMENTS, TO
WOOD & NATHAN COMPANY, OF NEW YORK, N. Y., A CORPORATION OF NEW YORK.

INTAGLIO AND RELIEF PRINTING DEVICE.

1,000,656.

Specification of Letters Patent. Patented Aug. 15, 1911.

Application filed December 10, 1906, Serial No. 347,028. Renewed December 12, 1910. Serial No. 596,969.

To all whom it may concern:

Be it known that I, HENRY A. WISE Wood, a citizen of the United States, residing at New York, in the county of New York and State of New York, have invented a new and useful Intaglio and Relief Printing Device, of which the following is a specification.

This case is in part a continuation of my application for patent on intaglio printing plate Serial No. 317,456, filed May 18, 1906.

My invention relates to improvements in intaglio printing, the particular objects thereof being to provide means whereby intaglio printing plates can be employed in the place of or in connection with, the relief printing plates or surfaces now in common use and to avoid certain complications which heretofore have been thought to be of such nature as to render such use of intaglio plates impracticable.

In the use of intaglio plates, the paper-contacting portion which contains the design and the non-printing portions heretofore have been one and the same surface, all located upon the same plane. The design is filled with ink and all surplus ink is removed from the plate by some wiping or scraping means. Obviously, it is of the utmost importance that the non-printing surface of the plate be free from ink before the printing operation is performed. This renders it necessary to keep the non-printing portion of the plate entirely free from scratches and other indentations which would fill with ink and print marks in the surface which should be clear. The use of a very high quality of copper in the preparation of these plates therefore is necessary and extreme care in their manipulation absolutely essential. In order to avoid these difficulties, I have produced a plate provided with a non-pressing and non-printing surface depressed below the paper-contacting surface, and provided with means whereby the scraping or wiping device may be gradually guided upon the paper-contacting surface in such a manner as effectively to clean the latter.

Reference is to be had to the accompanying sheet of drawings which illustrate mechanism for carrying out this invention and in which,

Figure 1 is a plan of a flat printing plate having relief and intaglio surfaces thereon

Fig. 2 is a sectional view of the same on the line 2-2 of Fig. 1. Fig. 3 is an end elevation of a printing cylinder having intaglio and relief surfaces showing their relations to each other and the relative position of the cleaning blade.

Referring first to Figs. 1 and 2, it will be seen that the printing plate is shown having thereon a raised paper contacting surface *a* which is provided with lines or engraving representing the intaglio design. It is of such form as to be capable of generation by the motion of a right line. It is surrounded or bounded on one or more sides by a non-pressing surface in a lower plane. Upon the same plate is also shown a design or composition in relief in the form of raised letters *b*. It will be seen that the upper surfaces of the letters *b* are in a lower plane than the surface of the design *a*. This is to provide for the use of a cleaning blade set so that it will clean the surface *a* without interfering with the ink on the surfaces *b*, both relief and intaglio parts of the plate being inked by the same inking roller. In the form shown in these two figures, the intaglio design preferably is surrounded by a fine line *a*² instead of being surrounded by a broad flat surface which has to be cleaned by the scraper. It will thus be seen that almost no surrounding paper impressing plane is left to be kept clean. In other words, around the design and about its outer edge, I leave a paper-contacting surface, preferably of not over one-thirty second of an inch in width and all of the out-lying plate is then brought to the plane of the non-pressing surface. The part inside the line *a*² is that in which the intaglio design is produced and has all the characteristics of an intaglio plate. Moreover, the surface or line *a*² rises out of the non-printing surface *c* preferably through a slanting surface *d* which engages the cleaning blade and gradually guides it to the surface which has to be cleaned. It is not intended, however, that the cleaning blade should come into contact with the surface *c* in the form shown in these two figures. This surface *d* is provided for the purpose of guiding a scraping or cleaning device gradually upon the paper contacting surface in such a manner that the forward edge of the latter shall be thoroughly cleaned and there shall be no sudden change of direction of the cleaning means.

On the rear side of the plate as it advances, another slanting surface preferably is employed to permit the cleaning means to descend from the paper-contacting surface 5 without leaving ink thereon.

In certain kinds of printing in which effects can best be produced by intaglio and relief surfaces, the best results can be obtained by placing, either on the same plate 10 with an intaglio design or on a separate plate, a relief surface for the ordinary kinds of printing. I have shown this feature in the form of a surface of the ordinary relief type directly on the plate which bears the 15 intaglio surface. The relief surface may be exactly the same height as the paper plane or paper-contacting portion of the intaglio surface, but I prefer to make it of slightly less altitude, as is indicated, so that there 20 will be no danger of the cleaning blade taking the ink from the relief surface.

As I have stated above, the relief surface may or may not be on the same plate as the intaglio surface, the principles of the invention 25 being complied with so long as they are printed from simultaneously.

For a further disclosure of the invention, reference is to be had to Fig. 3 which shows several printing plates mounted upon a 30 printing cylinder. The intaglio design is on a printing plate A while the relief design is on a printing plate B. These plates in this instance are shown as being formed separately and individually mounted on the cylinder. It will be noted that the printing surfaces of the plate B are in a lower plane, or at a shorter distance from the axis of the cylinder, than those of the plate A. This 35 is for the same purpose as that hereinbefore indicated. For the purpose of cleaning the surfaces of the intaglio plate or plates, a cleaning blade E is shown. This blade being mounted in the usual way which is well understood, will not be described in detail. The blade is so located that it will reach and 40 engage the surfaces of the intaglio plate or plates and will not interfere with the ink on the relief printing surfaces. It will be seen from a consideration of the drawings that 45 the relief and intaglio plates may either be separate plates or type may be employed surrounding the intaglio design or the two kinds of surfaces may be formed on the same plate. They can both be inked in the form 50 shown in Fig. 3 by a common ink supply F and impressed substantially simultaneously against a single impression member G, thus bringing the combined use of the two methods to the highest possible state of development. It will be understood, that instead of being inked from the same ink supply, two ink supplies may be used, each being adapted to touch only its own surface 55 to be supplied.

While I have illustrated and described

particular forms in which the invention may be embodied, I am aware that it may be carried out in other ways within the scope of the claims.

Having thus described my invention, what I claim is:

1. In a printing machine, the combination of intaglio and relief printing surfaces, the intaglio surfaces being higher than the relief surfaces, and a cleaning device set in position to engage the intaglio surfaces without touching the relief surfaces. 75

2. In a printing machine, the combination of a printing cylinder having intaglio and relief surfaces thereon, the intaglio surfaces being at a greater distance from the axis of the cylinder than the relief surfaces, a common ink supply for said surfaces, a cleaning device located to engage the intaglio surfaces and to not touch the relief surfaces, and an impression cylinder with 80 which the printing cylinder is adapted to engage. 85

3. As an article of manufacture a printing member having a relief printing surface, and an intaglio printing surface higher than the relief printing surface. 90

4. A printing member having an intaglio printing surface, and relief printing surface, the intaglio printing surface being in a higher plane than the relief printing surface, and having a non-printing surface and a slanting surface rising out of the non-printing surface into the intaglio printing surface. 95

5. A printing member having an intaglio printing surface, a relief printing surface, the intaglio printing surface being in a higher plane than the relief printing surface, in combination with means for inking 105 both surfaces, and means for cleaning the intaglio surface.

6. In a printing machine, the combination of a printing member having an intaglio printing surface and a relief printing surface lower than the intaglio printing surface, with a common inking device for both 110 of said surfaces.

7. In a printing machine, the combination of a printing cylinder having intaglio and relief surfaces thereon, the intaglio surfaces being at a greater distance from the axis of the cylinder than the relief surfaces, and a common ink supply for said surfaces. 115

8. In a printing machine, the combination of a printing cylinder having intaglio and relief surfaces thereon, the intaglio surfaces being at a greater distance from the axis of the cylinder than the relief surfaces, and a cleaning device located to engage the intaglio surfaces and to not touch the relief surfaces. 120

9. An intaglio printing plate having a non-printing non-pressing surface depressed below the paper-contacting surface thereof. 130

and connected therewith by a continuous gradual slanting surface.

10. A printing plate having a paper-contacting surface engraved in intaglio, raised above a surrounding non-pressing surface, two opposite edges of the raised surface being connected with the non-pressing surface by continuous gradual slanting surfaces.

11. An intaglio printing plate having a paper-contacting surface, and an inclined integral continuous slanting surface gradually rising into said contacting surface.

12. A printing plate having a complete intaglio design located entirely in a surface capable of being generated by the motion of a right line, and a narrow paper-contacting surface in the form of an outline following the contour of the design.

13. An intaglio printing plate having a narrow paper-contacting surface in the form of an outline surrounding the outer lines of the design, all the plate surrounding said outline being on a plane lower than that of the paper-contacting surface.

14. A printing plate having an intaglio design, and a narrow paper-contacting surface in the form of an outline surrounding the outer lines of the design, all the plate

surrounding said outline being on a plane lower than that of the paper-contacting surface, and a relief printing surface located in a plane lower than the plane of said paper-contacting surface.

15. A printing plate having a paper-contacting surface provided with an intaglio design, said plate also having a relief printing surface integral and continuous therewith and at a different elevation.

16. A printing plate having a paper-contacting surface provided with an intaglio design, said plate also having a relief printing surface located in a lower plane than said paper-contacting surface.

17. In a device for printing, the combination of a paper-contacting surface provided with a design in intaglio, and a continuous integral surface provided with a design in relief and located in a lower plane.

In testimony whereof I have hereunto set my hand, in the presence of two subscribing witnesses.

H. A. WISE WOOD.
